UNITED STATES PATENT OFFICE.

ELMER S. SHIMER, OF MILTON, PENNSYLVANIA, ASSIGNOR TO SAMUEL J. SHIMER & SONS, INC., OF MILTON, PENNSYLVANIA, A CORPORATION OF PENNSYLVANIA.

CUTTER-HEAD.

1,348,753.

Specification of Letters Patent.

Patented Aug. 3, 1920.

Application filed February 3, 1920. Serial No. 356,108.

To all whom it may concern:

Be it known that I, ELMER S. SHIMER, a citizen of the United States, residing at Milton, in the county of Northumberland and State of Pennsylvania, have invented 5 certain new and useful Improvements in Cutter-Heads, of which the following is a specification.

My invention relates to an improvement 10 in cutter heads.

There are several objects in view, one of which is the provision of a cutter head of a maximum degree of efficiency in the performance of its work, with the least possible 15 amount of trouble and danger to the machine operator.

Another object is to provide a cutter head of such a construction and a knife of such a form that the grinding for sharpening is 20 all on the front bevel and throughout the full thickness of the knife and as a result the cutting edge is always gaged with perfect precision as a part of the sharpening of the knife.

25 A further object is to provide a cutter head for endurance, that is in which the cutting edge can be made more durable than heretofore. In cutter heads hitherto in use it has been difficult if not impossible to secure a favorable cutting edge for endurance, for the reason that the edge of the knife came so near the square of the head that it produced a thin cutting edge that was frail especially in working hard woods, but in 30 this present invention the knife edge is set well back from the square of the head, which automatically changes the angle at which the edge of the knife is presented to the board, about twenty degrees, thus providing a more durable working knife edge.

Still another object is to provide a cutter head for the cutting of molding in which the back of the cutting edge remains unchanged in a given knife while the sharpening 45 all takes place upon the front bevel thus providing uniformity of cut throughout the use and life of a given knife and not requiring anything of the machine operator in the way of molding his own knives as has frequently been the custom.

With the foregoing and other important objects in view my present invention consists in features of construction which will be fully described and set forth in the 50 claims.

In the accompanying drawings, Figure 1, is a longitudinal section through the cutter head,

Fig. 2, is a transverse section,

Fig. 3, is a fragmentary view from one 60 end of the cutter head, and

Fig. 4, is a detail.

The body 1, of the cutter head is counter-bored through the longitudinal center 2, in the usual manner, to receive the shaft, not 65 shown, and in cross section it is more or less rectangular in form, in the construction shown, although it is understood that this depends on the number of knives that the head has, which in this particular instance are four, but the number of knives is obviously subject to variation. In this way two or more head sides are presented, according to the number of knives employed on a given cutter head. Each head 70 side is longitudinally grooved to form a track 3, and fitted to these tracks are the 75 slideable knife clamps 4, 5, in pairs, there being preferably two pairs of the clamps for each knife. The two members of each 80 clamp are substantially alike except that one member has a threaded hole 6, and the other member has a threadless hole 7, and the screw 8, is swiveled in the threadless hole 7 and threaded into the threaded hole 85 6, so that the turning of the screw 8, moves the inner clamp member, in or out, according to the way the screw is turned. The 90 clamp members 4, 5, are fashioned at the opposite edges to fit the track or way 3, and the upper edges of the clamps have dovetailed jaws 9, which face each other and are adapted to receive and clamp a portion of the knives therebetween. These dovetailed jaws 9, are made to ride back and 95 forth upon the head sides 10, which latter also form support for the bases of the knives. The bevel guide 11, is formed at the forward edge of each head side 10 as an integral part thereof, constituting a fixed 100 rib or gage, against which the knife is snugly set up and clamped.

The knives are of peculiar design and form the subject matter for a companion application, and yet they are with the cutter head designed to go together and since the knives illustrated are all alike in form and dimensions, in the further description they will be referred to, in the main, in the singular.

The numeral 12, represents the knife. It has its back or outer surface 13, fashioned to conform to the molding design to be cut, and starting back a predetermined distance 5 from the cutting edge the back of the knife is beveled, as at 14, to save unnecessary weight and also to provide clearance that may be necessary, to prevent the heel of the knife from striking. This does not in 10 10 otherwise decrease the working efficiency of the knife, as each knife is so constructed that it is good for about one inch of wear, and consequently any excess weight at the heel of the knife is superfluous, so that if 15 it is beveled off as shown, the base of the knife is not deprived of any of its holding properties. It will be observed that the beveling off of the molded portion of the back commences at a place on the knife 20 back where its further use would render it unsafe, thus automatically providing a means to signify to the operator that the knife is worn out.

On the underside or base of the knife the 25 dove-tailed webs 15, preferably two in number, are formed integral and extend in the direction of the travel of the knife, and the forward or cutting edge of the knife is beveled throughout its thickness, including the 30 webs as at 16, and this bevel 16, precisely corresponds in angle, to the angle of bevel guide 11, which forms a fixed rib or gage therefor, in the setting of the knife, and this 35 gaging continues with precision, throughout the use of the knife. In other words the grinding of the cutting edge of the knife extends to the webs and upon the same angle throughout, and always to fit the bevel guide 11.

40 The clamps 4, 5, are so disposed that their jaws 9, embrace and in fact clamp the webs 15, of the knives, against which they are drawn and held rigidly by the screws 8, which it has been explained turn freely in 45 one member and are threaded in the other member. In this simple manner it is possible to quickly clamp or unclamp the knife, by applying a wrench first at one end of the cutter head and then at the other end.

50 The depth of cut in this knife is provided for by a thickening of the knife, thereby doing away with much of the work and effort that heretofore was required of the operator himself, but with this tool becomes 55 a standardized article for its particular work. The arrangement of the knives is compact, as instead of having to project inches beyond the head sides, my present arrangement does not require that, and consequently as an agent of safety alone it adds 60 much to the comfort of the machine operator.

The usual clearance spaces 16', are provided in the surface of the cutter head.

I claim:

65 1. The combination with the body portion

of a cutter head including head sides in which tracks or ways are formed and having a bevel guide adjacent thereto, of a knife provided with dove-tailed webs on the base, the forward edge of the knife including the 70 webs being beveled so that the edge fits the bevel guide, and means fitted to the tracks or ways for clamping the webs.

2. The combination with the body portion of a cutter head including head sides and 75 bevel guides as a part thereof, of knives having a beveled forward edge the angle of which corresponds with the bevel guide when the base rests upon the adjacent head side.

3. The combination with the body portion of a cutter head including head sides in which tracks or ways are formed, and provided with bevel guides as a part of the head sides, of knives having beveled forward 85 edges adapted to rest upon said head sides and bevel guides and provided with webs on their under sides, and clamps slidable in the tracks or ways having jaws to engage and hold the webs therebetween. 90

4. The combination with the body portion of a cutter head including head sides in which tracks or ways are formed, and provided with bevel guides as a part of the head sides, of knives having beveled forward 95 edges having dove-tailed webs on their under sides adapted to extend in the direction of rotation of the cutter head and to rest upon the head sides, clamps adjustable in the tracks or ways, and means extending to the 100 opposite ends of the body portion and connected to the clamps for locking the clamps to the webs.

5. The combination with the body portion of a cutter head including head sides in 105 which tracks or ways are formed, and provided with bevel guides as a part of the head sides, of knives having beveled forward edges having dove-tailed webs on their under sides adapted to rest upon the head sides, clamps consisting each of two members fitted to slide and adapted to be adjusted in said tracks or ways, one of said clamp members having a threadless and the other a threaded 110 hole and each member having a dove-tailed jaw between which the webs are received and rigidly clamped, and screws extending through the members having the threadless holes and screwed into the members having the threaded holes with the outer ends thereof accessible to a tool whereby they are adapted to be turned to clamp or unclamp the jaws. 115

6. The combination with the body portion of a cutter-head, including head sides and provided with concaved clearance spaces between said sides, one edge of each head side beveled, of knives having beveled forward edges which conform to and fit the beveled portion of the head sides, and adjustable 120 125

means connected with the head sides for securing the cutters thereto.

7. The combination with the body portion of a cutter head including head sides in 5 which tracks or ways are formed, of knives, dove-tailed webs on their bases and their forward edges beveled through the webs, each head side having a beveled guide adjacent to the track or way corresponding in inclina- 10 tion with the forward edge of the knife and against which the latter is adapted to rest

while the webs rest upon the head sides, clamps fitted and adapted to slide and be adjusted in the tracks or ways and having dove-tailed jaws to receive and rigidly hold 15 the webs, the clamps each comprising two members, and screws swiveled to one of said members and screwed to the other for locking and unlocking the clamps.

In testimony whereof I affix my signature. 20

ELMER S. SHIMER.
